BUCKLE

Lawrence Del Ponte, Cranston, R.I., assignor to Anson,
Inc., Providence, R.I., a corporation of Rhode Island

Filed June 25, 1963, Ser. No. 75,513

Term of patent 14 years

(Cl. D17—1)

FIG. 1

FIG. 2

FIGURE 1 is a top plan view of a buckle, showing my new design, with a portion of a belt shown in broken lines for illustrative purpose only;

I claim:

The ornamental design for a buckle, as shown and described.
